UNITED STATES PATENT OFFICE.

GEORGIE DORSEY, OF SEATTLE, WASHINGTON.

TELEPHONE-MOUTHPIECE.

1,244,433.

Specification of Letters Patent. Patented Oct. 23, 1917.

Application filed January 12, 1917. Serial No. 142,101.

To all whom it may concern:

Be it known that I, GEORGIE DORSEY, a citizen of the United States, residing at Seattle, in the county of King, and State of Washington, have invented new and useful Improvements in Telephone-Mouthpieces, of which the following is a specification.

This invention relates to telephony, and more especially to antiseptic protectors for the mouthpiece; and the object of the same is to produce a protector of this character applicable to any of the ordinary forms of mouthpieces now in use, including a movable element whose upper portion is a shutter normally closing the bell of the mouthpiece and whose lower portion is a screen or comb which stands normally in an antiseptic and which is raised out of the same across the open end of the bell when this element is lifted in order to use the telephone.

Details are set forth in the following specification and claims, and in the accompanying drawings wherein:—

Figure 1 is a vertical sectional view showing this attachment applied to the mouthpiece of a telephone, the movable element being illustrated in full lines in its normal position and in dotted lines as raised as when the operator desires to use the phone.

Fig. 2 is a front elevation showing the shutter as raised.

In Fig. 1 is best seen the mouthpiece M of a telephone, whose front end is flared or shaped like a bell as at B, being usually applied to and removable from the body of the telephone itself, and it is into this bell that the operator speaks and usually inserts the lips and from it that it is believed germs are taken in the act of using the telephone. The purpose of the present invention is to provide a protector which normally closes this bell but which when raised to give the operator access thereto will interpose between the lips and the bell a screen bathed in antiseptic of suitable character.

Coming now to the details of the present invention, the numeral 1 designates a tank standing preferably below the bell B and containing an antiseptic which may be a liquid or a powder—preferably the former. An upright piece of sheet metal 2 may be pierced with a hole 3 for the reception of the shank or neck of the bell, and may be continued below the same to form the back 4 of

the tank, then bent at 5 and carried upward to form the front 6 of the tank, then bent at 7 and carried rearward to form the top 8 of the tank, and finally united at 9 with the back 2. When end pieces 10 are applied as indicated in Fig. 2, the tank is complete excepting that the top has a row of perforations or a slot 11 across it near the front 6. From time to time the antiseptic may be replenished by pouring it into the tank through the slot, or the top could be detachably united at 9 with the back 2, so that it could be raised for washing out the tank and replenishing it with antiseptic. These details are not important, but I describe one simple way of making the tank and the back plate, both of which are necessary to my invention.

Coating with the parts above described, is a movable element which also may well be made of sheet metal. Its upper portion is solid and constitutes a shutter 15 of a size and shape to amply cover the front end of the bell B, and one side of this shutter may have a slight projection constituting a handle 16. The lower portion of this element is reticulated, perforated, or otherwise formed into a screen; and by preference I provide it with longitudinal slots which produce interposed teeth so that the screen as shown herein is in reality a comb 17 whose tines are integral with the lower edge of the shutter plate 15. By preference the entire element is given a slight curvature, and the front wall 6 of the tank is given a corresponding curvature as best seen in Fig. 1.

It is possible to permit this movable element to act by gravity, but I prefer to employ a pair of coiled contractile springs 18 as best seen in Fig. 1, each connected at its extremities with the top plate 8 of the tank and the shutter 15 near the upper edge of the latter, and these springs standing on opposite sides of the mouthpiece or bell B so as not to interfere with the same. They may be detachably connected with the movable element so that when the latter is to be withdrawn or the entire device taken off of the telephone, the springs can be disconnected. A working proportion of parts is illustrated in the drawings, but I do not wish to be confined in this particular, nor to the details, proportions, or materials.

In action, this device is attached by removing the bell B and passing the hole 3

over the usually threaded shank of the mouthpiece M, and then restoring the bell. This holds the fixed element about the position seen in Fig. 1 and with the tank standing beneath the bell. The movable element is now brought into use and its screen or comb passed down through the slot 11 in the top plate 8, and the springs attached. Now when this element is released the 10 tractile action of the springs draws it downward to the position shown in full lines in Fig. 1, when the comb 17 passes down into the antiseptic within the tank and the solid portion or shutter 15 stands squarely 15 over the mouth of the bell B so that it is impossible to use the telephone. When an operator approaches, he grasps the handle 16 and raises the device to the position shown in dotted lines in Fig. 1 and in full 20 lines in Fig. 2, which action draws the comb out of the antiseptic and disposes it across the mouth of the bell; and thereafter he must speak through this comb which of course is saturated with the antiseptic, what- 25 ever the latter may be. Therefore he is positively prevented from pressing his lips against or into the bell, and even if he should place them against the comb he can not touch the bell and can only touch the 30 comb, which latter is covered with the antiseptic. This solution (or powder) should be something that is not objectionable to taste or smell, something that does not evaporate too readily, and something which is 35 not offensive in any way. While I have used the term "comb" herein, and have shown the lower portion of the movable element as slotted to produce tines or teeth which in effect would constitute a comb, it 40 is clear that the object of the invention is attained if this portion is reticulated, perforated, or otherwise rendered open to the passage of the voice, but closed to the lips. This portion of the movable element may 45 therefore be said in its fullest sense to be a screen, as that is its function. My attachment may be applied to most of the forms of telephone mouthpieces now in use, and in fact I do not wish to be limited to its 50 application to telephones, as it might be serviceable elsewhere as for instance, on the mouthpieces of other instruments or machines into which talking is done.

What is claimed as new is:—

- 55 1. An attachment for telephone mouthpieces comprising a chamber for an antiseptic, means for supporting it adjacent to the mouthpiece, a movable element whereof one end constitutes a screen normally housed 60 within the chamber and the other end constitutes a shutter normally standing over the mouthpiece, and means for permitting

movement of said element to draw the screen across said mouthpiece.

2. A mouthpiece for telephones and the like comprising a tank for an antiseptic, means for supporting it from and subjacent to the mouthpiece, a movable element whose lower end constitutes a screen normally submerged in the antiseptic within the tank and whose upper end constitutes a shutter normally standing over the front end of the mouthpiece, and means for raising this element to draw the screen across said mouthpiece. 75

3. A mouthpiece for telephones and the like comprising a tank for an antiseptic, means for supporting it from and subjacent to the mouthpiece, a movable element whose lower end is rendered open to the passage of sound and normally submerged in the antiseptic and whose upper end is closed and stands normally over the mouthpiece, and yielding means holding said element in such position, for the purpose set forth. 80

4. In an antiseptic mouthpiece for telephones and the like, the combination with an upright metal strap having an opening through which the mouthpiece passes, and a tank carried by the lower end of the strap, the top of the tank standing beneath the bell of the mouthpiece and having a slot across its front edge forward of said bell; of a movable sheet metal element passing through said slot, its lower end being longitudinally slotted to produce a comb and its upper end solid and standing normally over the front of said bell, and springs connecting the upper end of this element with the tank, for the purpose set forth. 95

5. In an antiseptic mouthpiece for telephones and the like, the combination with an upright metal strap having an opening through which the mouthpiece passes, and a tank carried by the lower end of the strap, the top of the tank standing beneath the bell of the mouthpiece and having a slot across its front edge forward of said bell, the front wall of said tank being curved; of a movable sheet metal element curved to correspond with the curvature of said wall and passing through the slot in the top of the tank, its lower end being longitudinally slotted to produce a comb and its upper end being solid and standing normally in front of the mouth of the bell, a handle formed on the upper end, and springs connecting the upper portion of the element with the tank and standing at opposite sides of the bell, for the purpose set forth. 110

In testimony whereof I affix my signature.

GEORGIE DORSEY.
